UNITED STATES PATENT OFFICE.

HARRY R. GEER, OF JOHNSTOWN, PENNSYLVANIA.

DRILLING MACHINE.

1,407,059.

Specification of Letters Patent. Patented Feb. 21, 1922.

Application filed March 10, 1920. Serial No. 364,630.

To all whom it may concern:

Be it known that I, HARRY R. GEER, a citizen of the United States, and a resident of the city of Johnstown, county of Cambria, and State of Pennsylvania, have invented certain new and useful Improvements in Drilling Machines; and I do hereby declare the following to be a full, clear, and exact description of the invention, such as will enable others skilled in the art to which it appertains to make and use the same.

My invention relates to improvements in multiple-spindle drilling machines of the adjustable gang type, in which the spindles are provided with means for adjustment whereby a plurality of holes may be simultaneously drilled. My invention is particularly adapted to drilling holes in the ends of railway rails or the like, but is not intended to be so limited or defined, as it may be used in other connections where it is desired to simultaneously drill a plurality of holes.

One of the objects of my invention is to provide a strong and rigid pillar construction which comprises the use of a right-hand threaded pillar and a left-hand threaded pillar, the lower portion of each of which is preferably square and is rigidly mounted in the bed frame or base of the drilling machine. The intermediate portions of the pillars are preferably cylindrical and together with the upper threaded portions guide and support a frame on which is mounted the working parts of the controlling and drilling mechanism of the machine.

Another object of my invention is to provide both automatic and manual means for the upward and downward travel of the frame on which the spindles and operating parts are mounted, and means for controlling the same whereby the drills may be raised, lowered or stopped at any point as desired, thus insuring desired ease, accuracy and speed of operation.

Other objects of my invention will appear hereinafter.

Having thus given a general description of my invention, I will now, in order to make the matter more clear, refer to the annexed six sheets of drawings which form part of this specification and in which like characters refer to like parts:

Figure 1 is a front elevation of my improved drilling machine; Figure 2 is an end elevation of the same; Figure 3 is a vertical sectional elevation taken on the line

III—III of Figure 2; Figure 4 is a vertical sectional elevation taken on the line IV—IV of Figure 2; Figure 5 is a horizontal sectional elevation taken on the line V—V of Figure 2; Figure 6 is a perspective view, to a larger scale, of a type of ball bearing I prefer to use, a portion of the casing being broken away to more clearly illustrate the construction; Figure 7 is a transverse sectional elevation of a type of roller thrust bearing I prefer to use; Figure 8 is a side elevation of the worm-gear which engages the worm on the central spindle shaft; Figure 9 is a vertical sectional elevation of the clutch-gear and worm-gear; Figure 10 is a side elevation of the clutch-gear; Figure 11 is a horizontal sectional elevation, to a larger scale, of the controlling mechanism showing the control-shaft broken away, this section being taken on the center line of the control-shaft; Figure 12 is a longitudinal sectional elevation showing in detail the arrangement of the cam mechanism on the hubs of the hand control-wheel; Figure 13 is an end elevation of the end of the control-shaft and the cam surfaces on the outer end of the hubs of the hand wheel; Figure 14 is a top plan view of a cruciform connector for the universal joints; Figure 15 is a longitudinal sectional elevation of one of the coupling spindles taken on the line XV—XV of Figure 19; Figure 16 is a transverse sectional elevation of the movable frame and the spindle roller bearings taken on the line XVI—XVI of Figure 1; Figure 17 is a side elevation of the cruciform connector for the universal joints; Figure 18 is a transverse section of one of the spindles and its journal bearing showing the rollers between the same; and Figure 19 is a transverse sectional elevation of one of the coupling spindles taken on the line XIX—XIX of Figure 15.

Referring now to the characters of reference on the drawings:—1 represents the front bed-frame to which is secured the back bed-frame 2 by the bolts 3. Channels formed in the front and back bed-frames, 1 and 2 respectively, and between the bolts 3 receive the preferably square lower portions 4 of a pair of pillars which extend upwardly and have intermediate preferably cylindrical portions 5. One of the pillars has an upper right-hand threaded portion 6 and the other an upper left-hand threaded portion 7. Top and bottom sleeves, 9 and 8 re-

spectively, are slidably mounted on each of the pillars while between these sleeves a sleeve nut 10 engages the threaded upper portion of the pillar. The sleeves 8 and 9 and the sleeve nuts 10 serve to guide and carry a frame 15 upon which is mounted the controlling and drilling mechanism. Upper and lower ball bearings, 13 and 14 respectively, placed between the sleeves 8 and 10 9 and the sleeve nuts 10 serve to minimize friction when the bevel gear 12, fastened to the flange 11 of the sleeve nut 10, is rotated thereby raising or lowering the frame 15.

15 The frame 15, which is bolted to the top and bottom sleeves, 9 and 8 respectively, has a lower flange 16 with openings through which the pillars pass and in which the lower ends of the bottom sleeves 8 set. The frame 15 also has an upper flange 17 with openings which receive the upper ends of the upper sleeves 9. The top flange 17 and the bottom flange 16 are further secured to the sleeves 8 and 9 by bolts through the lugs 20. The top flange 17 supports the motor 18 and is reinforced by the brace 19.

A pinion 22 secured to the shaft 21 of the motor 18 meshes with the drive gear 23 on the main drive shaft 25 and the gearing 30 is suitably enclosed for safety by the guard or casing 24. The main drive shaft 25 which is journaled in the roller bearing 27, has keyed to it the bevel gears 28, 29 and 30 which mesh with the bevel gears 31, 32 and 33 respectively. The gears 31 and 33 are keyed to the spindle drive shafts 36, provision being made for longitudinal adjustment to take up wear, etc., in the roller thrust bearings 34 and 35, which are housed 40 in the yoke 26 as shown and between the shoulders on the bevel gears 31 and 33 and the shoulder formed by the preferably enlarged head 37 on the spindle drive shafts 36. The enlarged head 37 of the spindle drive shaft 36 contains a groove which receives one segment of the cruciform connector 38, which has another segment that is integral with the first and preferably perpendicular thereto. This latter segment fits 50 into a groove in the preferably enlarged head 39 of the male part of the coupling spindle which has a partially threaded shank 40 entering the female part 42 of the coupling spindle, the projection therein being adjustable by the nuts 41, thus providing means for varying the length of the coupling spindle. The male and female parts 40 and 42 respectively, of the coupling spindle are prevented from rotating upon 60 each other by the feather 43 which is held in place by the sleeve 44 that is shrunk on the female part 42 of the coupling spindle.

The female part 42 of the coupling spindle has a preferably enlarged head 45 which 65 contains a groove adapted to receive one

segment of a connector 46 similar to the cruciform connector 38 heretofore described. The other segment of the connector 46 fits into a groove in the enlarged head 47 of the spindles 48. Each of the spindles 48 70 has a sleeve 49 shrunk thereon with rollers 50 at each end thereof and is journaled in the bearings 53. Fastened to the frame 15 is a guide 51 having a guide-way 52 that is provided with adjusting slots 54 through 75 each of which passes a bolt 55 that secures the spindle bearing 53 and its accompanying spindle 48 in position according to the drill spacing desired. Each of the spindles 48 is provided at its lower end with a drill 80 socket and a collar 56 which holds the lower set of the rollers 50 in place and also retains lubricant and excludes drillings, dust, etc., from the bearing.

The central spindle 57 is driven by the 85 bevel gear 32 at its upper end which is journaled in roller thrust bearings similar to 34 and 35, between the shoulder of the gear 32 and the flanged collar 58, provision being made for longitudinal adjustment to 90 take up wear, etc. The lower end of the central spindle 57 is journaled in the bearing 60 which is an integral part of the guide 51. The rollers 63 in the bearing 60 are retained by the top and bottom collars 95 62 and 61 respectively, which are secured to the lower part of the central spindle 57.

A connecting shaft 65 journaled in bearings 66 which are secured to the back of the frame 15 is provided with ball bearings 100 72, and has at its ends overhung bevel gears 67 which mesh with the bevel gears 12 secured to the sleeve nuts 10. The shaft 65 has mounted thereon a clutch-gear 68 and a worm gear 70 which meshes with a worm 105 59 on the central spindle 57. The clutch-gear 68 is prevented from rotating upon the shaft 65 by a feather, but it may slide longitudinally thereon. The worm-gear 70 is carried on the shaft 65 by the ball bearings 72 in its hub and it may rotate on or with the shaft 65, depending upon the position of the clutch-gear 68. The worm-gear 70 is provided with a plurality of radially disposed holes 71 which are adapted 110 to receive a lesser number of radially disposed pins 69 projecting from one side of the clutch gear 68, thereby forming a clutch to control the raising or lowering of the frame 15. 120

The engagement or disengagement of the clutch formed by the clutch-gear 68 and the worm-gear 70 is dependent upon manual operation by means of the control-shaft 73, the hand wheel 74 and the parts incidental 125 thereto. One end of the control-shaft 73 is journaled in the inner bearing 88 which is fastened to the front face of the movable frame 15 and the other end passes through the hubs of the hand wheel 74. The inner 130

bearing 88 is provided with a ball bearing 90 retained by the nut 89. The control shaft 73 is provided with a transverse hole 91 which contains a spring 92 between two friction disks 93 that bear against the inner race of the ball bearing 90, so that the control shaft 73 will rotate with and not in the race.

Meshing with the clutch gear 68 and keyed 10 to the control-shaft 73 is a spur pinion 86 which has an annular disk 87 securely clamped to each of its sides as shown in Figure 11. These annular disks 87 project over the ends of some of the teeth on the 15 clutch-gear 68 and thus engage it so that, when the control-shaft 73 is moved longitudinally, the clutch-gear 68 partakes of an equivalent longitudinal motion on the shaft 65, thus bringing into play the clutch action 20 between the clutch-gear 68 and the worm-gear 70.

In order that the control-shaft 73 may be moved longitudinally the outer end of the hub of the hand wheel 74 is provided with 25 cam surfaces 81 upon which rides a pin 85 passing transversely through the end of the control-shaft 73. The inner end 77 of the hand wheel hub is journaled in the outer bearing 75 which is provided with a roller 30 bearing 78 held on the hub by the nut 79, and the hand wheel 74 is held in the bearing 75 by the nut 76. Secured on the threaded portion 80 of the hand wheel hub is a hub cap 82 which houses a spring 83 that sets 35 in the recessed end 84 of the control-shaft 73, thereby holding the pin 85 against the cam surfaces 81 at all times.

The back bed-frame 2 has two upwardly projecting standards 94 between which is 40 fulcrumed a lever 95 on the pin 96. The front end of the lever 95 has hinged thereto by the pin-bolt 98 two rollers 97 which roll on the wearing plate 99 that is fastened to the bottom flange 16 of the frame 15. The 45 rear end of the lever 95 carries an adjustable counterweight 100, which is thus adapted to relieve the loading on the pillars so as to reduce the friction between the threads 6 and 7 and the sleeve nuts 10 when the frame 50 15 is raised or lowered.

The work to be drilled is placed on the table of the front bed plate and secured thereto by the clamping arrangement indicated by 64.

Assuming that the frame 15 is substantially in its lowest position as shown on the drawings, the operation of my machine is as follows:—The frame 15 on which is mounted 55 the drilling mechanism may be raised to clear the work by turning the hand wheel 74 clockwise, facing the wheel. Clockwise rotation, as stated, of the hand-wheel 74 will cause the pin 85 to ride up on the cam surfaces 81 on the hand-wheel hub, thus re- 60 tracting the control-shaft 73 and disengag-

ing the clutch formed by the worm-gear 70 and the clutch-gear 68. Further rotation of the hand wheel 74 will rotate the shaft 65 and the bevel gears 67 thereon which mesh with the bevel gears 12 on the sleeve nuts 70 10, thus raising the frame 15.

The weight of the counterweight 100 exerted at all times on the wearing plate 99 fastened to the lower side of the flange 16 of the frame 15 helps to balance the weight of 75 the drilling and operating mechanism so as to reduce the friction between the threaded portions 6 and 7 of the pillars and the sleeve nuts 10 thereon.

After the frame 15 has been raised sufficiently to clear the work to be drilled, the hand-wheel 74 is released, whereupon the spring 83 will return the shaft 73 to the position shown by the full lines in Figure 11, thus engaging the clutch formed by the 80 clutch-gear 68 and the worm-gear 70. The adjustable spindles 48 are set to the required spacing by moving their bearings 53 in the 85 guide 52 and adjusting the length of the coupling spindles by the nuts 41. The necessary drills are then set in the spindles and the drill press is prepared to drill the work which is securely clamped on the receiving 90 table of the front bed-frame 1 by the clamping device 64.

The motor 18 rotates the spindles by the spur gears 22 and 23 and through the drive shaft 25 which is geared to the spindles by the bevel gears 28, 29 and 30 which mesh with the bevel gears 31, 32 and 33 respectively. The central spindle 57 is a through shaft provided with a worm 59, thereon that engages the worm-gear 70 which is locked to the clutch-gear 68 as stated above. The motor 18 now rotating the spindle 57 will 105 cause the shaft 65 to rotate thereby lowering the frame 15 and automatically feeding the drills to the work. After the holes are drilled the frame 15 with the drilling mechanism thereon may be raised to clear the 110 work as heretofore described.

The drills may be stopped at any time during the operation by turning the hand-wheel 74, a part of a turn in either direction, thereby retracting the shaft 73 and disengaging the clutch formed by the clutch-gear 68 and the worm-gear 70. The worm-gear 70 then runs idle on the shaft 65 and the motion of the frame 15 ceases. It is evident that the drill feed may be automatic or 120 manual or a combination of both, depending upon the permissible cutting speed, thus insuring flexibility of operation.

It is therefore evident that my improved drilling-machine is capable of handling a 125 wide range of work in a thoroughly satisfactory manner, because of the great flexibility provided by the automatic as well as the manual control. Furthermore the ease with which adjustments may be made in- 130

sures not only rapid and efficient operation, but provides also a maximum of safety for the operator, and insures a minimum of spoiled work.

5 Although I have described and illustrated my invention in considerable detail, I do not wish to be limited to the exact and specific details thereof as shown and described, but may use such modifications in, substitutions 10 for, or equivalents thereof, as are embraced within the scope of my invention, or as pointed out in the claims.

Having thus described my invention, what I claim and desire to secure by Letters 15 Patent is:—

1. In a drilling-machine, a stationary base, upwardly projecting pillars mounted therein and provided with threaded portions, a sleeve-nut on each pillar engaging the 20 threaded portion thereof, sleeves surrounding the pillars at each end of said sleeve-nuts, a movable frame attached to said sleeves, drilling mechanism mounted on said frame and means for raising and lowering 25 the same.

2. In a drilling-machine, a stationary base, pillars secured thereto and provided with threaded projections extending therefrom, a nut on the threaded portion of each pillar, 30 sleeves surrounding the projecting portions of each pillar and attached to the nuts, a movable frame secured to the sleeves, drilling mechanism mounted on the movable frame, and means whereby the nuts may be 35 simultaneously rotated to advance or retract the drilling mechanism.

3. In a drilling-machine, a base, pillars secured thereto and provided with threaded portions projecting therefrom, a nut on the 40 threaded portion of each pillar, sleeves surrounding the pillars at each end of each nut, said sleeves attached to and supported by the nuts, a movable frame provided with top and bottom flanges secured to said 45 sleeves, drilling and operating mechanism on said movable frame and means for rotating the nuts simultaneously whereby the motion of the movable frame is controlled.

4. In a drilling-machine, a base, pillars 50 secured thereto and provided with threaded portions projecting therefrom, a nut on the threaded portion of each pillar, a gear secured to each of the nuts, a shaft provided with gears meshing with the gears on the 55 nuts, means for rotating the shaft, sleeves surrounding the pillars at each end of each nut, said sleeves attached to and supported by the nuts, a movable frame provided with top and bottom flanges secured to said 60 sleeves and adapted to carry the drilling and operating mechanism, means for rotating the nuts simultaneously to advance or retract the drilling mechanism, and means for controlling the feed of the drilling mechanism.

65 5. In a drilling-machine, a base, pillars

secured thereto and provided with threaded portions projecting therefrom, a nut on the threaded portion of each pillar, a bevel gear secured to each of the nuts, a shaft provided with bevel gears mounted thereon and adapted to mesh with the bevel gears on said nuts, means for rotating the shaft, sleeves surrounding the pillars at each end of each nut, said sleeves attached to and supported by the nuts, a movable frame provided with top and bottom flanges secured to said sleeves and adapted to carry the drilling and operating mechanism, means for rotating the nuts simultaneously in either direction for advancing or retracting the drilling and operating mechanism, and means for controlling the feed of the drilling mechanism. 70

6. In a drilling-machine, a base, pillars secured thereto and provided with threaded portions projecting therefrom, a sleeve nut 85 on the threaded portion of each pillar, sleeves surrounding the pillars at each end of each nut, said sleeves attached to and supported by the nuts, a frame secured to said sleeves, spindles mounted on the frame, 90 means for rotating the spindles, and means for simultaneously rotating the nuts on the pillars for advancing and retracting the spindles.

7. In a drilling machine, a base, pillars 95 secured thereto and provided with threaded portions projecting therefrom, a nut on the threaded portion of each pillar, a sleeve at each end of each nut on the projecting portion of the pillars which is retained in position by the nuts, a frame secured to the sleeves, spindles mounted on the frame, means mounted on the frame for rotating the spindles, means for simultaneously rotating the nuts on the pillars for advancing 100 or retracting the drill spindles and means for controlling the rotation of the nuts on the threaded portions of the pillars for advancing or retracting the drilling mechanism. 110

8. In a drilling machine, a base, pillars secured thereto and provided with threaded portions projecting therefrom, a nut on the threaded portion of each pillar, a sleeve surrounding the pillars on each end of each 115 nut which is retained in position by the nuts, a frame secured to the sleeves, spindles journaled in bearings mounted on the frame, means mounted on the frame for continuously rotating the spindles, means for rotating the nuts from the rotating spindles, and means for controlling the rotation of the nuts on the threaded ends of the pillars for advancing or retracting the drilling mechanism. 120

9. In a drilling machine, a base, threaded pillars secured thereto, a nut on the threaded portion of each pillar adapted to rotate thereon, a connection between the nuts for simultaneously rotating the same, a sleeve 130

on either side of each nut on the pillars abutting against the end of each nut, a frame with top and bottom flanges secured to the sleeves at the sides and ends thereof, spindles journaled in bearings mounted on the frame, means for continuously rotating the spindles mounted on the frame, means for rotating the nuts on the pillars from one of the rotating spindles for advancing the frame and 10 the drilling mechanism mounted thereon, and means for controlling the rotation of the nuts and for retracting the frame and the drilling mechanism mounted thereon independent of the means for rotating the 15 spindles.

10. In a drilling-machine, a base, threaded pillars secured thereto and projecting therefrom, means thereon for supporting a movable frame, spindles journaled in bearings 20 on said frame, means for rotating said spindles, an automatic means and a manual means independent thereof for controlling the longitudinal motion of said spindles.

11. In a drilling-machine, a base, pillars 25 secured therein and provided with threaded portions projecting therefrom, a sleeve nut on the threaded portion of each pillar, a sleeve surrounding the pillars at each end of each sleeve nut and attached thereto, a 30 bevel gear secured to each sleeve nut, a

flanged frame attached to the sleeves, a cross shaft mounted on said frame and secured to said sleeve nuts, spindles mounted on said frame, a worm on the shaft of one of said spindles, a worm gear on said cross shaft 35 that may engage said worm, means for rotating the spindles, a slidable control shaft mounted on said frame and provided with a hand wheel and clutch arrangement for engaging or disengaging the worm-gear and 40 worm, thereby providing either automatic or manual control for the longitudinal movement of the spindles.

12. In a drilling-machine, a base, pillars secured thereto, a movable frame supported 45 by said pillars, automatic means for raising or lowering said frame on the pillars, spindles rotatably mounted on said frame, means for rotating said spindles, a worm on the shaft of one of the spindles, a slidable 50 cross shaft mounted on the movable frame and provided with a hand wheel and clutch for disengaging the automatic lowering and advancing means, thereby providing manual control for the longitudinal movement of 55 the spindles.

In witness whereof I hereunto affix my signature.

HARRY R. GEER
